Joseph Nicolas
Letters Patent

This is a Continuation in Part of my Letters Patent No. X6600, making part of the same, containing a description in the words of the said, Joseph Nicolas, of his improvement in the method of destroying plants, insects, or other animals, native to the Americas and particularly the noxious plants, known by the names of coca, coca gramine, coca tuberosa, coca hybrida, &c. It consists of 1st ploughing the field infested with the above noxious plants, insects or other animals to the depth of eight or ten inches more or less, according to the soil. 2nd On a carriage moved by team or other power upon which a steam boiler is fast to which boiler is adapted a fine pump moved by steam or otherwise to convey water in. The boiler undone or several pipes to convey the steam from the boiler to any described portion of the surface ploughed. The heat of the steam instantaneously effects the destruction intended. If the first suspension or sprinkling be not sufficient for obtaining the desired effect (which is very seldom the case,) the ploughing and sprinkling of steam must be repeated.
